UNITED STATES PATENT OFFICE.

JOHN MURSCH AND CHARLES F. SCHUTTE, OF UTICA, NEW YORK, ASSIGNEES TO
BUFFALO HAMMER MILL CORPORATION, OF BUFFALO, NEW YORK, A CORPORATION OF NEW YORK.

CENTRIFUGAL FAN.

Application filed August 16, 1927. Serial No. 213,238.

This invention relates to improvements in centrifugal advancing mechanism, in particular to the centrifugal fan used therewith.

It is one of the primary objects of the invention to provide a device of this character which will operate with greater efficiency and with the requirement of less power than those heretofore in use.

It is a further object to provide a construction which will operate satisfactorily for a greater period of time by reducing the wear upon the parts thereof.

More specifically the invention contemplates the provision of improved radial blades extending outwardly and rearwardly from the axis of rotation of the advancing fan and to provide stepped surfaces on the contact surfaces of these blades and to connect the stepped surfaces of said blades with a supporting disk thus forming a rugged construction and one operating in a superior manner to prior constructions.

These and other objects will appear more fully from the following description considered in connection with the drawings in which:

Fig. 1 is an elevational view of a mill showing the application of the invention.

Fig. 2 is an end elevational view of the fan wheel.

Fig. 3 is a vertical view taken at right angles to Fig. 2, parts being in section on the line 3—3 of Fig. 2.

Fig. 4 is a fragmentary section taken on the line 4—4 of Fig. 2.

This invention is useful in connection with a wide variety of mechanisms for advancing products, for example with all kinds of grinding mills such for instance as feed mills, ore or clay or other grinding or advancing mechanisms, the present invention in this respect not being limited to any particular mechanism but being adapted, with slight changes, to a wide variety of uses.

Referring to the details of the drawings, there is diagrammatically illustrated a portion of a feed mill 6 to which my invention is applied. The advancing mechanism is supported within the housing 8 and is fed adjacent the axis thereof from a suitable conducting pipe 9, the fan or advancing element 11 receiving the material and discharging the same through an outlet pipe as indicated for example at 10. The use and relation of

these parts will be readily recognized by those skilled in the art and does not differ from the uses of other centrifugal advancing devices.

The centrifugal mechanism includes a supporting disk 12 formed with a central hub portion 14 adapting the same to be mounted upon any suitable rotatable shaft. The fan blades indicated generally at 16 are preferably formed integral with the disk 12, there being provided any desired or suitable number of blades and the blades and disk being properly proportioned for the particular use for which the device is intended.

It will be seen from Fig. 2 that each fan blade 16 is curved outwardly and rearwardly from the portions thereof nearest the axis of rotation of the disk, this construction providing a more powerful and a perfectly operating device than straight radial or inclined blades, as heretofore in use.

Each of the blades 16 is formed with a forward or contact surface 18 which, as shown, is formed with a plurality of stepped portions 20, the successive stepped portions of the contact surface being positioned rearwardly of each radially inward section as clearly indicated in Fig. 2. The portions 20 are thus separated by means of the steps 22. The stepped portions 20 extend substantially across the blades 16, the inner edge of each portion 20 being curved forwardly adjacent the supporting disk 12 as indicated at 23, (see Fig. 4) thus continuing the stepped relation to the disk but without the formation of objectionable pockets.

In operation the disk and attached blades are rotated at the desired relatively high speed in the direction of the arrow (Fig. 2) the force of the currents produced being sufficient to draw the material from the mill, through the passage 9, and into the housing 8 and fan 11. The material passes into the fan adjacent the axis thereof, the outward currents of air and the contact of this material with the fan blades causing the material to pass outwardly through the passage 10. As the material passes outwardly through the fan between the blades 16 it is brought forcibly into contact with the fan blades the stepped relation of which prevents any continued contact between the fan blade and the material being advanced. This elimination of most of the direct contact is sufficient to

materially reduce the power required and to insure longer life for the apparatus than with those heretofore in use.

While we have shown and described certain specific constructions as illustrations of our invention it will be understood that variations therefrom may be made so long as they fall within the scope of the claims appended hereto. We may contemplate the use of entirely different constructions for different uses but the principle of our invention will remain the same.

Having now described our invention, we claim:

- 15 1. In a centrifugal advancing mechanism, a rotatable fan formed with a series of radially outwardly directed blades provided on their forward faces with stepped surfaces.
- 20 2. In a centrifugal advancing mechanism, a rotatable fan formed with a series of radially outwardly directed blades provided on their forward faces with stepped surfaces, said surfaces being stepped outwardly and rearwardly with respect to one another.
- 25 3. In a centrifugal advancing mechanism, a rotatable fan formed with a series of radially outwardly directed blades, each provided on its forward face with a plurality of outwardly and rearwardly stepped surfaces for the purpose set forth and a disk formed integrally with said blades and extending along one side edge thereof and of said stepped surfaces for supporting the same.
- 30 4. In a centrifugal fan, a rotatable blade the contact surface of which is curved rearwardly as it extends outwardly from the axis of rotation thereof, said blade having different portions of the contact surface thereof offset with respect to other radially removed portions of the surface thereof.
- 35 5. In a centrifugal fan, a rotatable blade

the forward surface of which extends outwardly and rearwardly from a point near the axis of rotation thereof, said forward surface including elevated and depressed portions 45 providing a broken forward surface thereon.

6. In a centrifugal fan, a rotatable blade the forward surface of which extends outwardly and rearwardly from a point near the axis of rotation thereof, said forward 50 surface being separated into a plurality of outwardly and rearwardly spaced or stepped portions.

7. In a centrifugal fan, a rotatable blade, the forward surface of which extends outwardly and rearwardly from a point near the axis of rotation thereof, said forward surface being separated into a plurality of outwardly and rearwardly spaced or stepped portions, 55 a rotatable disk secured to said blade and rotatable therewith, the steps joining said spaced or stepped portions extending forwardly from said surface to a predetermined extent along said disk.

8. In an advancing mechanism, a fan comprising a rotatable supporting base and a plurality of advancing members, each formed with a series of contact surfaces positioned in stepped or offset relation for successive engagement by the material being advanced. 60

9. In an advancing mechanism, a fan comprising a plurality of series of contact surfaces, each series being formed with radially separated, circumferentially spaced contact 65 portions, spaced successively outwardly and rearwardly of one another.

Signed at Utica, in the county of Oneida and State of New York, this 10th day of August, A. D. 1927.

JOHN MURSCH.
CHAS. F. SCHUTTE.
